UNITED STATES PATENT OFFICE.

NELSON BLOUNT, OF JAMESTOWN, RHODE ISLAND, ASSIGNOR TO THE GOVERNMENT
OF THE UNITED STATES.

GYROSCOPIC STEERING MECHANISM.

Application filed August 18, 1920, Serial No. 404,482. Renewed September 27, 1924.

To all whom it may concern:

Be it known that I, NELSON BLOUNT, a citizen of the United States, residing at Jamestown, Rhode Island, have invented new and 5 useful Improvements in Gyroscopic Steering Mechanism, of which the following is a specification.

This invention relates to improvements in torpedoes and more particularly to improvements in the steering mechanism of the Whitehead or Bliss-Leavitt torpedo now in 10 general use as a weapon of naval warfare.

The more recent developments of torpedoes of the above character, the exact construction and operation of which is at present largely a matter of military secrecy, provides certain means whereby the course of the torpedo may be changed under certain circumstances at some period of time materially after the launching of the torpedo. 15

As is well-known to those familiar with the art, the steering of a torpedo of the above type is automatically controlled by and through the medium of a gyroscope which is 20 so connected with the steering rudders through the usual steering engine as to maintain the torpedo on almost an absolutely straight line, all variations therefrom being but a few feet to the mile. In the mechanism now employed the gyro wheel operates 25 through a mechanism, including a cam to rapidly oscillate a pallet in a general longitudinal direction. Any movement of the gyro due to a change in course will cause 30 the pallet to also move about an axis at an angle to the line of oscillation. When such movement takes place other mechanism connected with the steering engine is actuated 35 to bring the torpedo back upon its true course. 40

As above stated, under certain circumstances, it is desirable that the torpedo should leave its true straight line course sharply either to the right or left and the 45 present invention contemplates a mechanism whereby the control of the gyro upon the steering engine may be instantaneously and temporarily suspended while what may be termed the auxiliary control mechanism 50 is connected with the steering engine to control the torpedo on its diverted course.

It is, therefore, one of the objects of the present invention to provide a simple and

practical mechanism of the above general type which will be reliable and efficient in 55 use and operation.

A further object is to provide a mechanism of the above character having relatively few parts compactly arranged which may be easily manufactured and assembled 60 and installed in the present type of torpedo without making material alterations in the present arrangement and location of other essential parts.

A further object is to provide a mechanism of the above character so mounted, positioned and arranged with respect to the gyro and steering engine as to permit an instantaneous change from one control to the other in either direction as circumstances 65 require, whereby greater accuracy and efficiency is obtained in the firing of the torpedo towards the target.

Other objects will be in part obvious and in part hereinafter pointed out. The invention accordingly consists in construction and arrangement of parts and the relation of each part to the other parts as will be hereinafter described in connection with the accompanying drawings showing one of various possible embodiments of the invention. 70

In these drawings wherein similar parts are indicated by corresponding reference characters,

Figure 1 is a detail view. 85

Figure 2 is a sectional view taken on the line 1—1, Figure 1.

Figure 3 is a view of auxiliary pallet.

Figure 4 is a fragmentary view of the upper part of Figure 1 with the slot plate removed. 90

Figure 5 is a sectional view taken on the line 3—3, Figure 1.

Figure 6 is a sectional view on line 2—2, Figure 1, of such parts of the complete mechanism as is necessary to understand the present invention. 95

Referring now to these drawings in detail there is denoted at 1 a plate on which are mounted the usual gyroscope pallet pawls 100 2 and 3 connected by means of adjusting studs 4, partially shown and screw 5. On the plate 1 are also mounted a second pair of pawls 6 and 7 being at the opposite side of the plate 1 and shown more clearly in Figure 105 6. These pawls are connected by means of a

link similar to and lying directly under link 8, Figure 1, which connects a third set of pallet pawls 9 and 10 mounted above and on the same fulcrum pins 11 and 12 as the 5 second set of pawls 6 and 7. The movement of any pawl is then equal and opposite to that of the connected pawl by means of their common link connections and no adjustments of the second and third set of pawls are required as in the case of the gyro pawls 2 10 and 3. The pawl 7 of the second set is connected by means of a screw pin 13 to link 14 which in turn is connected by a pin 15 and a link 16 to a pin 17 in the arm of the gyro 15 pallet pawl 3. Thus movement can then be transmitted to the pin 15 by either pawl acting independently or simultaneously, without transmitting a corresponding movement to the connected pawl. This will perhaps be 20 more clear by the double dotted and dash lines in Figure 4.

On the top of link 16 is a plate 18 with the diagonal slot 21 adapted to be connected to the steering engine valve stem by means of 25 the hole 19 and to the pallet pawl 10 of the third set by means of a screw pin 20. The pin 15 enters the diagonal slot 21, in the plate 18, whose dimensions are slightly 30 larger than the diameter of the pin. Slot 30 29 at the end of the plate 18 acts as a guide for the back and forth movement of the slotted plate 18 over the pin 17.

The gyroscope pallet 22 which normally 35 has a reciprocating movement substantially along the line 1—1 is mounted upon the upper end of the pallet shaft 23 which passes through a pallet holder 24 and is given the reciprocating movement above mentioned by means of the usual pallet slide 40 and cam not shown. This pallet shaft 23 is rotated by the action of the gyro sufficiently to engage the pallet on its outward or forward stroke with one or the other of the gyro pallet pawls 2 or 3. Entirely 45 separate and free from the gyro pallet but carried and driven by the pallet holder is a second pallet 25 mounted on a shoulder 26 of the pallet holder, by means of a ring portion 27 as will appear more clear from 50 the disclosures in Figures 2 and 3. The fit of the ring 27 on the shoulder is sufficiently free to permit the pallet to rotate easily. The reciprocative movement of the second pallet is equal but opposite to any 55 stroke of the gyro pallet.

The dimensions of the blade of the second pallet 25 are such as to enable it to engage both the second and third pallet pawls simultaneously. Back of the end of the 60 blade, however, are two shoulders 28, Figure 3, of such height as to engage only the lower set of pallet pawls 6 and 7. In the neutral position shown the blade of the 65 second pallet 25 is free to pass between both the second and third sets of pallet pawls.

At the full stroke of the pallet the shoulders 28 touch the lower pawls 6 and 7 and maintain these in balanced or neutral position. These in turn hold the pin 15 by means of the link 14 in a central position between the 70 parallel shoulders of the diagonal slot 21 in the plate 18. This neutral position of the second pallet is maintained by a connection not shown but fitted in a hole 30 and connected with the auxiliary control mechanism. Movement is also impressed on the pallet by the same connection. In this manner the operation of the auxiliary control steering mechanism will instantly disconnect the steering effect of the gyro through the normal pallet pawls 2 and 3. 75

A brief statement of the operation of the mechanism is as follows:—Under the influence of the gyroscope the gyro pallet 22 is shifted sideways with respect to its reciprocations to engage one or the other of the pallet pawls 2 and 3 and movement is transmitted therefrom to the steering engine through the pin 17, link 16, pin 15 to the shoulders of the diagonal slot 21 in the 80 slotted plate 18 and thence to the valve stem connected through the hole 19, as shown in Figure 1.

As long as the pin 15 is in the center position the gyro controls the steering engine. 95 If the second pallet 25 is shifted in either direction to engage one-half of the second and third sets of pallet pawls, the pawl 6 or 7 shifts the pin 15 by means of a link 14 out of the center position, and the pawls 9 or 10 directly connected to the steering engine by the screw pin 20 and the valve stem connected in the hole 19 of the slot plate 18, control the steering engine. The gyro 100 is thereby disconnected from the steering engine, since any movement of the gyro pawls 2 or 3 results only in the free movement of the pin 15 in one-half of the diagonal slot 21, with no movement of the slot plate 18. 105

To restore the steering engine control to the gyro the second pallet 25 is returned to the neutral position. One of the shoulders 28 of the second pallet engages the advanced pallet pawl 6 or 7 and returns it to a balance 110 position as regards its opposite and the pin 15 is thereby returned to the central position by sliding in the diagonal slot 21 and the control of the steering engine is restored 115 instantly to the gyro.

Each backward movement of the pallet brings the shoulders 28 of the second pallet to a position just clear of the pawls 6 and 7 at the full back stroke. Therefore, the central position of pin 15 is maintained and any movement out of position is instantly corrected. Since the to and fro motion of the pallet holder is exceedingly rapid the 120 operation of the mechanism is nearly instantaneous. 125

From the above it will be seen that the present invention provides a simple and practical mechanism adapted to instantly shift the steering control of the torpedo 5 from either the gyro to the auxiliary steering mechanism or vice versa. The mechanism comprises a small compact arrangement of parts which may be easily applied to the torpedoes now in use without material 10 alteration or disarrangement of the mechanisms now therein contained.

Without further analysis, the foregoing will so fully reveal the gist of this invention that others can by applying current knowledge 15 readily adapt it for various applications without omitting certain features that, from the standpoint of the prior art, fairly constitute essential characteristics of the generic or specific aspects of this invention, 20 and, therefore, such adaptions should and are intended to be comprehended within the meaning and range of equivalency of the following claims.

What I claim is:—

25 1. In a torpedo, in combination, a gyro, a steering mechanism and means whereby the action of the gyro on the steering mechanism may be temporarily neutralized during the run of a torpedo.

2. In a torpedo, in combination, a gyro, a 30 steering engine controlled thereby and means for disconnecting the gyro from the steering engine, including a plurality of pallets associated with the gyro.

3. In a torpedo, in combination, a gyro, 35 a steering engine controlled thereby and means for disconnecting the gyro from the steering engine, including a plurality of pallets associated with the gyro, said pallets being independent of each other.

4. In a torpedo, in combination, a gyro, a steering engine controlled thereby and means for connecting and disconnecting said gyro with said steering engine, comprising 40 a plurality of sets of pallet pawls and a plurality of pallets coacting therewith.

5. In a torpedo, in combination, a gyro, a steering engine controlled thereby and means for connecting and disconnecting said gyro with said steering engine, comprising 50 a plurality of pallets coacting therewith, said pallets being independently mounted movable with respect to each other, one of said pallets normally reciprocating neutrally between one of said sets of pallet pawls. 55

Signed at Newport, Rhode Island, this 19th day of June, 1920.

NELSON BLOUNT.
